Patented Nov. 2, 1920.

UNITED STATES PATENT OFFICE.

MARY M. McGREGOR, OF PASADENA, CALIFORNIA.

OIL-WELL FISHING-TOOL.

1,357,508.

Specification of Letters Patent.

Patented Nov. 2, 1920.

Application filed March 5, 1919. Serial No. 280,872.

To all whom it may concern:

Be it known that I, MARY M. McGREGOR, a citizen of the United States, residing at Pasadena, in the county of Los Angeles and State of California, have invented new and useful Improvements in Oil-Well Fishing-Tools, of which the following is a specification.

This invention relates to fishing tools for well drilling apparatus, and consists in the new and useful features and in the novel construction, arrangement and combination of parts, the advantages of which will be apparent from a consideration of the preferred form of construction herein shown, described and claimed.

The principal object of the invention is to provide a simple and positive means for easily and quickly removing under-reamer lugs, bolts or other small objects which may have accidentally fallen into or been displaced in, the bottom of the well.

In the operation of sinking oil wells hard stratas of rock are likely to be encountered and under-reamers are used to enlarge the hole. Said under-reamers have lugs that are apt to become loosened from the under-reaming tool and to fall into the hole. This is only likely to occur in formations where the bottom of the hole is hard and the lug can not be driven out of the way but must be removed. Various appliances have been provided for the purpose of removing such lugs but this invention is broadly new, basic and primary in its character in that I provide the tool with fingers which are adapted to pass down and around the sides of the objects to be removed and to be bent underneath said object by the application of such pressure or force as can be applied by the usual jars of a well drilling rig. To this end the fingers are constructed of material such as steel having a stubborn upper portion and being reduced toward the points of the fingers and being at the lower ends or points of such construction and temper that they may be given by the jars, a permanent set or crimp underneath the object to be removed. These fingers are slightly resilient

under such pressure as may be exerted by hand or by means not capable of applying great force, but the temper of the lower ends of the fingers is such as to allow such lower ends to be given a permanent set when driven down against the hard rocky bottom of the hole by means of the powerful appli-

cation of force which can be exerted by the usual jars of a well drilling rig.

Other objects, advantages and features of invention will appear from the drawing, the subjoined detail description and the appended claims.

The drawing illustrates the invention.

Figure 1 is a broken sectional view of the bottom portion of a well in which an under-reamer lug has been lodged; and showing the well casing in section and the fishing tool in vertical section and in its first position of enveloping the lug to be removed from the well.

Fig. 2 is a section taken on line x^2 of Fig. 1, showing the means used for attaching the fishing tool to the shank of a drill bit.

Fig. 3 is a broken sectional view of the bottom portion of a well similar to that shown in Fig. 1, and showing the fishing tool moved to a final enveloping position under the lug which is to be removed from the well.

Fig. 4 is a section on line x^4 of Fig. 1 with parts omitted.

Fig. 5 is a section on line x^5 of Fig. 4.

Fig. 6 is a detail of the lower end of one of the fingers of the fishing tool showing a preferred shape of said ends.

In detail, the well 1 is shown drilled into hard substance 2, such as rock or the like, through which deep wells have to pass. In the upper part of the well is shown the casing 3 having on its lower end the drive shoe 4 the purpose of which is to facilitate the lowering of the well casing, when the well has been enlarged by reamers, not shown, but which are well understood as to function and operation, the casing following the drills and reamers downward as they form the well, resulting in a very heavy column of pipe from near the bottom of the well to its top, which piping would require considerable time and labor for removal in order to remove an obstruction.

These obstructions usually consist of under-reamer lugs, broken drill bits, bolts or other hard objects which are small enough to allow them to be drawn up through the well casing if properly grappled; and this invention consists in providing means for so removing such obstructions without removing the casing.

As shown in Fig. 1, there is attached to the jar rod 5 one end of the bit 6 whose lower end is threaded to fit into the threaded socket 7 of the fishing tool 8.

To the lower edge of the head 9 of the fishing tool 8 and integral therewith, are the fingers 10 which are distributed at equal distances around said head. I prefer to use 5 six of these fingers but do not limit the invention to that number as any other number of fingers may be used. These fingers extend downward a considerable distance from the head and are tapered to a sharp point 10 at their lower ends which are spread outward beyond the interior circumference of the well casing; so that in inserting the fishing tool the fingers will have to be sprung inwardly. The fingers are adapted at the 15 lower ends to be given a permanent set at the bend but are constructed with enough resilience to spring them outward again when they have passed below the bottom of the casing, giving them a slightly wider 20 grappling radius. The length and taper of the fingers admit of this slight resilience, but their temper is not sufficient to prevent the points from being bent, and given a permanent set so that they will remain in a bent 25 position when driven down with sufficient force to give them a permanent set or crimp. And it is this feature which constitutes the effectiveness of my invention. Fingers of any other shape or conformation may be 30 used without departing from the spirit of my invention, provided they are so tempered as to enable the operator to produce the same effect.

As shown, the drill 6 has the cut away 35 sides 11 common in drill bit construction, to allow the passageway 12 between the drill and the base of the fishing tool for mud and water 13 to pass. This mud and water line is shown as being slightly above the fishing 40 tool, for the sake of clearness, but it is usually much higher.

In operation, assuming that the lug 14 has accidentally fallen to the bottom of the 45 well 1 and is to be removed before drilling can be resumed, the fishing tool 8 is attached to the bit 6 and the latter secured to the jar rod 5. The fingers 10 are then compressed until they will enter the well casing 3. The fishing tool is then forced downward until 50 the fingers 10 expand below the bottom of the casing and envelop the lug 14, as shown in Fig. 1.

By operating the jars the lower ends of the fingers will be bent or crimped so as to 55 extend from numerous sides underneath the object to be removed and will be given a permanent bend, set or crimp so that when the fishing tool 8 is drawn out, the permanently bent ends of the finger tips will carry 60 out the object to be removed.

It will be seen from the foregoing that an obstruction may be removed from a well very easily and quickly and in a very short time.

65 When the fishing tool has been removed

from the well the fingers may be heated and straightened out so as to release the object, thus removed. Thereupon the fingers may be again bent into the form adapted to the purpose above described.

70 By the old method of pounding the lug into fragments it required many days of time and labor to clear the well of the obstructions; and oftentimes such laborious efforts were unsuccessful owing to fragments of the lug being pounded into the rock and being dislodged above the drill, locking the drilling mechanism and causing the well to be abandoned.

75 My invention eliminates all this arduous labor of clearing the well of obstructions; and accomplishes this object with maximum ease and speed and minimum labor and expenditure of time, and is broadly new and basic in principle.

80 The invention admits of modifications, and a right is claimed to all such as do not depart from the scope and spirit of my invention.

85 I claim:

1. In a fishing tool for wells, a head; and a plurality of fingers secured to said head and adapted to be permanently bent around and made to grapple an obstruction in the well.

90 2. In a fishing tool for wells, a head; a plurality of fingers adapted to bend under pressure, secured to said head and adapted to envelop an obstruction in said well; and means for permanently bending said fingers around said obstruction.

95 3. In a fishing tool for wells, a head; a plurality of fingers integral with said head, said fingers being adapted to envelop an obstruction in said well; and means for forcing and holding said fingers around said obstruction.

100 4. In a fishing tool for wells, a head; a plurality of fingers extending downward from said head and adapted to envelop an obstruction in said well; means for forcing the fingers down the well and for bending said fingers about said obstruction for the purpose of removing said obstruction from the well.

110 5. In a fishing tool for wells, a head; a plurality of fingers extending downward from said head and adapted to envelop an obstruction in a well, said fingers being adapted to be bent under pressure within a well; means for lowering said fingers into the well to envelop an obstruction; and means for bending said fingers around said obstruction.

115 6. In a fishing tool for wells, a head; a plurality of fingers equidistant around the bottom of said head, said fingers extending downward and adapted to envelop an obstruction in a well, and adapted to be bent under the obstruction by a downward pres-

sure; means for lowering said fingers in the well; and means for bending said fingers around the obstruction for the purpose of removing it from the well.

7. In a fishing tool for wells provided with a well casing; a head; a plurality of fingers equidistant around the bottom of said head, said fingers tapering downwardly to points and adapted to envelop an obstruction, and to be bent therearound under pressure, the points of said fingers being normally extended beyond the interior diameter of said well casing.

8. A fishing tool for wells, comprising a head adapted to be attached to a driving rod and movable in a well provided with a casing; said driving rod; malleable fingers rigidly attached to said head, the free ends of the fingers being inturned and normally sprung outwardly beyond the casing; and means controlled by the operator to cause the fingers to be contracted to clutch an obstruction and hold it for removal from the well.

9. Means for removing obstructions from a well provided with a casing, comprising in combination, a jar rod adapted to operate in the casing; a threaded head detachably fixed to said rod; bendable and resilient fingers rigidly attached to said head provided with inturned, sharpened ends adapted to be bent under an obstruction and there given a permanent set by means of down-

ward pressure exerted by the jar rod upon said fingers pressing the same against the hard bottom, and adapted to be thereby bent around an obstruction at the bottom of the well and to preserve a clutch upon the obstruction to enable the same to be drawn up through the casing by means of the jar rod.

10. In a fishing tool, in combination with a head; malleable clutching members radially contractible under downward pressure, and adapted to be given a permanent set to retain such contracted position until expanded by the operator.

11. In a fishing tool, a body member; malleable radial clutching members so shaped that endwise pressure against them will cause them to be contracted radially and coördinately, and to receive a permanent set so as to remain in such clutching position until expanded by manual force.

12. A fishing tool having bendable fingers adapted to be permanently bent toward each other at the lower ends to clutch a loose obstruction at the bottom of a well by pressing the lower ends of said tool against the bottom of the well, for the purpose of grapping and removing an obstruction.

In testimony whereof I have hereunto set my hand at Los Angeles, California, this 27th day of February 1919.

MARY M. McGREGOR.

Witness:

WILLIAM M. GENTLE.
